UNITED STATES PATENT OFFICE.

GEORGE FRANCIS NYE, OF McCOOK, NEBRASKA.

THRASHING MACHINE.

Application filed August 13, 1925. Serial No. 50,073.

My present invention relates to machines for thrashing all kinds of small grain, and has for its primary object the provision of a small light readily portable apparatus which will effectively accomplish the complete separation of grain from straw, and which will avoid the many disadvantages of the heavy cumbersome thrashers now employed for this purpose.

10 A further object is the provision of a thrashing machine which will be inexpensive both in first cost and up-keep and which embodies a construction and arrangement of parts insuring its continuous and effective 15 operation without the disadvantages of choking and jamming commonly incident to small machines for the same purpose.

Another object is the provision of a machine embodying therein a continuous air 20 passage and a suction feed pipe together with means for creating a suction through the air passage and through the feed pipe whereby in the construction and arrangement as proposed by my invention the material handled within the machine will not exceed at any time the amount capable of being drawn in by the suction whereby to avoid the danger of an overload at any time.

25 A still further and more specific object of my invention is the provision of a thrashing machine including a thrashing disc in conjunction with certain means adapted to bring about a constant uniform distribution of the grain being thrashed, and further employing certain parts so arranged and related as to bring all moving portions into substantially a unit and in this way avoid the complicated features of the usual 40 thrasher. The thrasher proposed by my invention embodies a simple compact apparatus and necessitates but little power as compared to that usually required.

With the above general objects in mind, the further objects and resulting advantages of my improved thrashing machine may be better understood and more thoroughly appreciated from the following description and the accompanying drawings which illustrate my present invention and form a part 50 of this specification.

In these drawings,

Figure 1 is a perspective view illustrating a possible application of the invention in practice.

Figure 2 is a central vertical longitudinal section through the machine.

Figure 3 is a rear elevation thereof.

Figure 4 is a vertical transverse section through the separating chamber taken on line 4—4 of Figure 2.

Figure 5 is a detailed section taken on line 5—5 of Figure 4.

Figure 6 is a vertical transverse section taken on line 6—6 of Figure 2, and

Figure 7 is a similar view taken on line 7—7 of Figure 2.

Referring now to these figures my invention proposes a thrashing machine including two adjacent cylindrical casings 10 and 11 of which the forward casing 10 forms a separating chamber 12 therein, and the latter or rear casing 11 has therein a suction fan 13. The fan 13 is mounted upon a portion of an axial shaft 14 extending through both casings and mounted in bearings 15 on the front wall of the forward casing 10, and the rear wall to the rear casing 11, the forward bearing 15 appearing in Figure 2 as a portion of one wall of a feed pipe 16 which opens into the slightly conical front wall 17 of the casing 10 at the center thereof and around the shaft 14.

The inner surface of the slightly conical front wall 17 near its periphery is provided with an annular series of corrugations 18 and has within its corrugated portion a series of rearwardly projecting pins and the like 19 for cooperation in practice with the similar oppositely projecting and staggered pins 19 of a thrashing disc 20 which is also secured upon the same shaft 14 within the separating chamber 12 adjacent to and opposing the conical front wall 17. The disc 20 is provided upon one face with a series of corrugations 21 adjacent to its peripheral edge opposing the corrugations 18.

At its lower portion the casing 10 has a grain pocket 22 as most plainly seen in Figure 4 and in communication with this pocket is an upwardly and outwardly inclined grain discharge pipe 23 in which a bucket elevator 24 operates around inner and outer shafts 25 and 26, the buckets of the elevator taking the grain therein from the grain pocket 22 as they round the inner shaft 25. This shaft 25 is extended laterally and suitably connected by a belt to the rear end of the shaft 14 rearwardly beyond the rear casing 11.

Through the rear wall of the forward casing 10 and adjacent to the lower portion thereof an arcuate slot 27 opens into the lower enlarged portion of a pipe 28 forming 5 a communicating air passage between the casings 10 and 11, its smaller end opening at 29 into the front wall of the rear casing 11 axially thereof and around the shaft 14 whereby the suction fan 13 in action draws 10 a continuous current of air through the apparatus from the receiving mouth of the suction feed pipe 16.

The rear casing 11 outlets at the lower portion of one side of its wall into an upwardly and outwardly inclined discharge pipe 30 for the straw and chaff. By reference again to Figure 2 it is to be particularly noted that irrespective of whether or not the thrashing disc 20 is flat, a thrashing 20 space is formed between the same and the substantially conical wall 17 with which it co-operates, which widens radially as it narrows axially whereby to maintain a constant velocity and even air pressure throughout the thrashing space with the result that the material to be thrashed will be uniformly distributed throughout the active surface of the thrashing disc and so spread out and assisted by centrifugal action at the 25 periphery of the disc as to permit the air current to effectively separate the thrashed grain from the straw.

It will also be noted in particular that upon passage of the air beyond the periphery of the thrashing disc it merges into a 35 relatively large chamber 12 which I term the separation chamber and in which the velocity of the air is, of course, greatly reduced, permitting the heavier grain to immediately fall to the bottom of such chamber whereby it readily finds its way into the grain pocket 22 for distribution into sacks or the like fixed to or placed beneath the outer end of the grain discharge pipe 28. 40 At the same time the straw and chaff is carried through the communicating pipe 28 and into the fan cylinder 11 from which it is thrown by the action of the fan with outgoing currents through the straw and chaff 45 discharge chute 30.

The machine as thus described may as a whole be mounted upon a bed plate 31 which may be in turn disposed upon a truck or the like 32 as in Figure 1 for ready transportation from place to place by means of a tractor, and for operating purposes the thrashing machine of my invention may take the small power required thereby from the tractor for instance through a belt 33 which 55 engages a pulley 34 secured upon the forward end of the shaft 14. This it is to be understood is simply an illustrative manner of use, and the machine may if so desired be mounted in the first instance upon a wheeled frame, either with, or without its

own power locomotion, which if used will naturally be employed to drive the shaft of the thrasher.

It is obvious that in operation the suction developed by the fan serves to feed un-thrashed grain uniformly to the action of the parts and only in such amount as these parts are prepared to take care of. As the unthrashed grain is thus fed into the thrashing cavity or space between wall 17 and disc 20 it is moved directly in the space by the suction and thus distributed evenly for the cooperating action of the thrashing pins 18 and 19. As the thrashed material approaches the outer narrow circular opening between the outer edge of the thrashing disc and the adjacent wall of the casing it is spread out over a relatively large area by centrifugal force action and by opposing the direction of the air current induced by the suction brings about complete separation so that the straw and grain entering the relatively large separating chamber 12 in a separated condition permits the heavier grain to readily fall into the grain pocket while the lighter straw and chaff flow with the air current through the communicating pipe 28 and fan casing to be finally discharged.

The machine in so far as the actual thrashing of the grain is concerned obviously employs movable parts which rotate as a unit, thus avoiding the many independent moving parts required in the usual thrashing machine, so that the necessary power is thus greatly reduced.

It is likewise obvious that a thrashing machine constructed in accordance with my invention will be low in first cost as well as up-keep, and will not only be effective and efficient in operation, but will be strong and durable in use.

What I claim is:—

1. A thrashing apparatus including a pair of adjacent cylindrical casings, a shaft rotatable axially through said casings, an air pipe in communication between the lower portion of one of said casings and the central portion of the other casing, a fan secured on the shaft within the last mentioned casing for exhausting air from the first casing through said air pipe, said fan casing having a discharge opening at its side, a thrashing disk secured on the shaft within the first casing in spaced apart opposing relation to one wall of the casing, and forming between the same and the said wall of the casing a conical thrashing cavity through which material to be thrashed is distributed by the suction of the air exhaust fan, a feed pipe for the material to be thrashed opening centrally through the said wall of the casing into the thrashing cavity, said disk and the opposing wall of the casing having co-acting means forming beaters and having opposed annular corrugated

portions at the periphery of the disk, forming between them a narrow slot like discharge from the thrashing cavity opening into the first mentioned casing, and said 5 first mentioned casing having a grain pocket in its base for the reception of the thrashed grain.

2. A thrashing machine comprising a rotatable thrashing element contained within 10 a continuously enclosed air blast passage, means of delivering a restricted air blast at a central opening of this air passage, causing a radial air suction to act within a conical thrashing element, discharging from 15 the periphery of said element into a separation chamber which is an enlargement of the continuously enclosed air passage, means of creating an air exhaust attached to the outer end of a conduit opening in the bottom 20 of the said separation chamber which conduit forms a restriction at the rear end of the continuous air passage.

3. A thrashing machine comprising a separation chamber, a hopper containing 25 means to close the air suction at the bottom of said chamber, in communication therewith, a thrashing disk at one end of said chamber, means of receiving grain through an opening in the center opposite this disk 30 and means of creating an air suction through the central opening through the space enclosed by the disk through the circular opening at the periphery through the thrashing chamber and through a conduit 35 in the bottom of the thrashing chamber, a suction fan in communication with said conduit.

4. A continuously enclosed air passage 40 thrashing machine comprising an enlarged thrashing chamber, a restricted conduit connecting an enlarged exhaust chamber a transverse rotatable shaft supporting a radial thrashing element within said thrashing chamber and an exhaust fan within said 45 exhaust chamber, an inlet opening into the thrashing chamber, a discharge opening out of the exhaust chamber in combination forming an air blast carrier conduit, wherein the action of said exhaust fan draws 50 the unthrashed grain into said inlet opening and ejects the thrashed straw and chaff from said discharge opening.

5. A thrashing machine including a vertical 55 rotatable disk and a vertical stationary member facing one another in opposing spaced apart relationship forming a vertical thrashing and separation cavity, having an intake conveyor flue attached to the stationary member and a discharge around the peripheral edge of the disk, means for creating an air blast through the conveyor flue inlet, through the thrashing and separation cavity and through the said peripheral opening whereby said air blast separates the straw

from the grain kernels as they pass from 65 the peripheral opening.

6. A thrashing machine including a vertical enclosed housing, a vertical disk thrashing and separation element mounted within 70 said housing, a flue conveyor extending from said housing and forming a continuously enclosed air passage, means for creating an air suction through the conveyor flue, through the space between the vertical wall of the housing and the face of the said disk 75 and through the space between the peripheral edge of the disk and the housing, whereby the thrashed grain is thinned as it is carried by the air suction radially over the face of the disk and over the peripheral 80 edge of said disk enabling the air suction to separate the straw from the grain kernels.

7. In a thrashing machine, a vertical rotatable disk thrashing element, a vertical 85 housing for said element, a flue conveyor extending centrally from said housing and forming therewith an air conveying enclosure, means for creating an air suction, whereby unthrashed grain will be drawn through the flue into the space between the disk and the housing spreading it radially 90 by centrifugal action as it is thrashed whereby said air suction separates the straw from the grain kernels as they are being discharged from the peripheral edge of said 95 vertical thrashing element.

8. A thrashing machine comprising a vertical air conveying housing and including a vertical rotatable disk thrashing member mounted therein said air conveying housing having an inlet opening opposite the center of said disk, a thrashing cavity formed by the vertical wall of said housing and said vertical disk and extending from the said inlet opening to the periphery of the disk, the peripheral opening constituting a connection between said thrashing cavity and a separation chamber defined on the opposite side of the disk and the air conveying housing, means for creating an air 100 suction to convey grain through the inlet, through the thrashing cavity, through the peripheral opening between the disk and the housing and through the separation 105 chamber.

9. A thrashing and separation machine comprising an enclosing housing and including an intake flue opening through one wall of said housing, a vertical rotatable disk mounted in said housing and dividing the housing enclosure into thrashing and separation compartments, said compartments connected by an opening around the peripheral edge of the disk, a discharge opening from the separation compartment, and means for creating a suction air blast through the intake flue, through the thrashing compartment, through the peripheral opening, 110 115 120 125

through the separation compartment and discharge opening whereby when unthrashed grain is sucked into the inlet flue the straw is ejected from the separation compartment

5 through the discharge opening.

10. A thrashing machine comprising thrashing and blowing compartments, a rotatable vertical disk mounted in said thrashing compartment, a common drive 10 shaft passing through said compartments, an external inclined conduit leading from the bottom of the thrashing compartment to the blowing compartment, and discharge means extending from the blowing compartment.

15. A thrasher comprising thrashing and blowing compartments, a vertical rotatable disk mounted in said thrashing compartment, said disk dividing the compartment 20 into a thrashing chamber and a separation chamber, a peripheral passage connecting the said chambers, a thrashed grain receiving pocket at the bottom of said thrashing compartment, a common drive shaft passing 25 through said compartments, an external inclined conduit leading from the bottom of the thrashing compartment to the blowing compartment, and a chaff and straw discharge means leading from the blowing compartment.

30. A thrashing machine including thrashing and blowing compartments, a rotatable vertical disk mounted in said thrashing compartment, a common drive shaft 35 passing through said compartments, an external inclined conduit leading from the bottom of the thrashing compartment to the blowing compartment, discharge means leading from the blowing compartment,

the centrifugal force action of the disc opposing the direction of the air blast at its periphery whereby to produce separation of the grain under treatment.

13. A thrashing machine comprising a pair of opposed thrashing elements arranged in axial alignment, one of said elements being rotatable and capable of developing marked centrifugal force action, an expansion chamber at the rear of said elements, an inlet flue leading to and through the center of one said elements, there being a restricted annular discharge opening at the peripheries of the elements, means for creating an air blast through the inlet flue and uniformly through the space between the elements and across the peripheral discharge opening, the centrifugal force action of the rotatable element opposing the direction of the air blast at the periphery, whereby to cause separation of the grain.

14. A thrashing machine comprising a pair of opposed thrashing elements arranged in axial alignment one of said elements being rotatable, an expansion chamber at the rear of said elements, an inlet flue leading to and through the center of one of the said elements, there being a restricted discharge at and between the peripheries of the respective elements, means for creating suction through the inlet flue and uniformly through the space between the said elements, and out the peripheral opening, the centrifugal force action of the rotatable opposing the direction of the suction at the periphery, whereby to cause separation of the grain.

GEORGE FRANCIS NYE.
